INVENTOR.
William Knight
BY *George D. Walker*
ATTORNEY

UNITED STATES PATENT OFFICE.

WILLIAM KNIGHT, OF RIO VISTA, CALIFORNIA.

DOOR LATCH.

Application filed November 23, 1921. Serial No. 517,179.

To all whom it may concern:

Be it known that I, WILLIAM KNIGHT, a citizen of the United States, residing at Rio Vista, county of Solano, State of California, have invented certain new and useful Improvements in Door Latches; and I do declare the following to be a full, clear, and exact description of the same, reference being had to the accompanying drawings, and to the characters of reference marked thereon, which form a part of this application.

This invention relates to improvements in door latches, and is particularly intended as an improvement over that form of latch shown in my Patent No. 1,407,758, dated February 28, 1922, the present device operating on the same principle as the other.

20 The principal object of the present invention is to provide a latch device more particularly adapted for house doors rather than automobile doors, as was the former (though it may be used for this and other purposes as well), in which the construction is simplified over the former type, and which is provided with handle release-means for the latch which may be operated by a turning movement either to the right or to the left.

Another object of the invention is to provide a simple lock member to hold the latch-bar against movement either when it is in a neutral or retracted position, or when it is extended, this lock member being capable of being actuated by means of an ordinary key either by itself or used in connection with whatever standard cylinder or pin lock mechanism which it may be desired to install.

A further object is to provide a latch and locking means therefor in whose construction the use of springs, with their tendency to break or weaken, is eliminated.

45 A further object of the invention is to produce a simple and inexpensive device and yet one which will be exceedingly effective for the purposes for which it is designed.

50 These objects I accomplish by means of such structure and relative arrangement of

parts as will fully appear by a perusal of the following specification and claims.

In the drawings similar characters of reference indicate corresponding parts in the 55 several views.

Fig. 1 is a fragmentary perspective elevation of a door adjacent the side edge, showing my improved latch installed therein.

Fig. 2 is a side elevation of the latch box 60 with a side cover plate removed, showing the latch-bar as normally held in neutral position, when the door is open.

Fig. 3 is a similar view, showing the 65 position assumed by the latch bar when the door is closed, and with the latch-lock also engaged therewith.

Fig. 4 is a similar view, showing the latch bar as being partially retracted or moving 70 to a neutral position.

Referring now more particularly to the characters of reference on the drawings, the numeral 1 denotes a suitable casing or box adapted as usual to be set in a door 2 and provided with an edge plate 3 positioned flush with the free side-edge of the door.

Pivotedly mounted in the casing is a latch bar 4, so proportioned that of its own weight it will, if allowed to do so, project through 80 a slot 5 in the plate 3 and seat in a similar slot 6 in the usual co-operating jamb-plate 7 secured in the door casing. This bar however is normally held flush with the plate 3 by means of a ball 8 thereabove, slidably 85 mounted on an upwardly sloping track 9 in the casing, and adapted to project partially through an orifice 10 in the plate 3 above the slot 5, the ball, by reason of the force of gravity, normally seating thus in 90 the orifice and so projecting beyond the plate 3, the ball in that position being in front of the upper end of the latch 4, and thus preventing the latter from dropping out of its slot. In operation then, with the parts 95 in the last named position, as soon as the door is moved adjacent its casing, the projecting surface of the ball strikes the casing and the ball is moved upward on its track, freeing the latch 4 and allowing it to drop 100 through the slot 5 into the slot 6.

To retract or release the latch, I provide

any suitable form of handles 11, preferably on both sides of the door, and fixed on a shaft 12 turnably mounted with respect to the casing 1 and extending therethrough.

5 Fixed on this shaft within the casing is a sleeve 13 having opposed arms 14 thereon, each at a time being adapted to bear against a lever 15 pivoted intermediate its ends in the casing 1, the opposite end of the lever 10 from the area of bearing of the arms 14 thereagainst being provided with an upturned nose 16 adapted to bear against the edge of the latch 4 at a point thereon intermediate its pivotal connection and its outer 15 edge adjacent the plate 3.

To hold the latch bar 4 positively against movement in either of its two extremes of position, I provide a horizontal arm 17 pivoted at one end in the casing and below the 20 latch 4 and lever 15. This arm has a lug 18 thereon adapted to seat in either one at a time of recesses or notches 19 cut in the under edge of the latch 4, these notches being both equidistant from the pivotal point 25 of the latch, and being positioned to lie in vertical alinement with the lug 18 when the latch 4 is either extended or retracted.

Normally, the lug 18 is clear of said notches, but may be moved to seat therein 30 by means of a plate 20 slidable in the bottom of the casing under the arm 17 and adapted to be moved along by means of a small arm 21 turnably mounted in the casing and adapted to bear against a transverse cross 35 bar 22 formed with the plate 20.

This arm 21 may be the usual flat offset lug formed at one end of an ordinary key of the old fashioned type, or it may be fixed in connection with one of the many standard and more or less burglar proof lock 40 mechanisms as indicated at 23, and which are adapted to receive only their own particular keys.

When the plate 20 is moved in one direction by movement of the arm 21, a raised lug 24 on said plate passes under and bears against the lowest point of the lock-arm 17, causing the same to be lifted and the lug 18 thereon to seat in whichever one of the latch- 45 notches 19 is in alinement therewith at the time. When the plate 20 is moved in the opposite direction, by reverse manipulation of the key member or arm 21, the lug 24 is removed from under the arm 17, and the 50 latter then falls of its own weight, releasing the latch 4 and permitting the latter to move when released by the movement of the ball or raised by movement of the lever 15.

As previously stated, no springs of any 55 nature are needed for the successful operation of the device, all movements of the various parts in one direction taking place by reason of the force of gravity.

However, if it is intended to mount this 60 latch in an automobile or other door in which

a certain amount of vibration will be had, I preferably place a weak coil spring 25 behind the ball, not to aid in the operation thereof, but to prevent any rattling of the same, due to the vibration of the door, which 70 might be annoying to anyone within hearing.

The cross bar 22 preferably projects beyond both sides of the plate 20, so that if desired, a key may be inserted from the opposite side of the door, or another lock mechanism such as 23 may be mounted on that side as well.

From the foregoing description it will be readily seen that I have produced such a 80 device as substantially fulfills the objects of the invention as set forth herein.

While this specification sets forth in detail the present and preferred construction of the device, still in practice such deviations from such detail may be resorted to as do not form a departure from the spirit of the invention, as defined by the appended 85 claims.

Having thus described my invention, what 90 I claim as new and useful and desire to secure by Letters Patent is:

1. A door latch including a lock bar, means whereby the bar may be moved to a retracted or an extended position, an arm 95 thereunder, a lug on said arm positioned to aline with either one at a time of notches provided in the adjacent edge of the bar, a plate slidably mounted under the arm, and means whereby when said plate is moved in 100 one direction the arm will be moved to seat the lug thereon in one of said notches.

2. A door latch including a lock bar, means whereby the bar may be moved to a retracted or an extended position, an arm 105 thereunder, a lug on said arm positioned to aline with either one at a time of notches provided in the adjacent edge of the bar, a plate slidably mounted under the arm, a lug on the plate adapted to bear against 110 and raise the arm when the plate is moved in one direction, and key actuated means for so moving the plate.

3. A door latch including a lock bar, means whereby the bar may be moved to a 115 retracted or an extended position, an arm thereunder, a lug on said arm positioned to aline with either one at a time of notches provided in the adjacent edge of the bar, a plate slidably mounted under the arm, 120 means whereby when said plate is moved in one direction the arm will be raised to seat the lug thereon in one of said notches, and a cross bar projecting from the plate adapted to be engaged by a turnable key-arm. 125

4. A door latch including a lock bar, means whereby the bar may be moved to a retracted or extended position, an arm thereunder, a lug on said arm positioned to aline with either one at a time of notches pro- 130

vided in the adjacent edge of the bar, a plate slidably mounted under the arm, a lug on the plate adapted to bear against and raise the arm when the plate is moved in one direction, and key actuated means for so moving the plate, means whereby when said plate is moved in one direction, the arm

will be raised to seat the lug thereon in one of said notches, a cross arm projecting from the plate, and a turnable arm positioned to bear against the cross bar, said arm being adapted to be turned by a key.

In testimony whereof I affix my signature.

WILLIAM KNIGHT.
